JOHN F. HUGHES, OF DARBY, PENNSYLVANIA.

AUTOMATIC DUMPING AND READJUSTING WAGON.

1,130,735.

Specification of Letters Patent.

Patented Mar. 9, 1915.

Application filed November 11, 1908. Serial No. 462,043.

To all whom it may concern:

Be it known that I, JOHN F. HUGHES, a citizen of the United States, residing at Darby, county of Delaware and State of Pennsylvania, have invented a certain new and useful Improvement in Automatic Dumping and Readjusting Wagons, of which the following is a specification.

My invention relates to dump wagons and other vehicles in which the body has pivotal connection with its supporting frame whereby it may be tilted to discharge its contents. In previous constructions of this character, in so far as I am aware, it has been necessary to apply some force other than gravity to cause the body to tilt to discharge its load and to cause the readjustment of the same to its normal position.

The object of my invention is to provide a wagon which will automatically discharge its contents or load and readjust itself to normal position when the driver withdraws the latch or trigger or other means which may be used for holding the body in its normal position. Other dumping wagons of this character which have been heretofore constructed require, as already indicated, some force other than and in addition to gravity to cause the body to completely and automatically perform the acts of tilting to discharge the contents or load and readjustment to normal position. The operation of discharging the contents or load from the wagon body or receptacle heretofore has generally been performed in three distinct acts,—first, by tilting the body, usually by hand, to a dumping position; second, the dumping of the load which is an act of gravity; and third, the readjustment of the wagon body or receptacle which may be performed in various ways. By the employment of my invention these acts of tilting the body, discharging the contents or load therefrom, and the readjustment of the body or receptacle to its normal position are performed by the action of gravity and require no other force to effect a complete operation. The peculiar and novel construction and arrangement of the parts of the structure embodying my invention make this possible.

In a structure embodying my invention the body of the wagon rests upon a pivotal support so situated with reference to the length of the body that the center of gravity of the body is in front of the plane of the

pivotal axis of the body when it is empty, while the center of gravity of the combined weights of the body and its contents or load is situated in rear of such pivotal axis. In the structure embodying my invention I have also provided means for utilizing the tail-board of the wagon as a counter-weight whereby a sufficient amount of energy may be accumulated to readjust the body to its normal position after the load is dumped or discharged.

As already indicated, the relation of the center of gravity of the body when empty and of the combined weight of the body and its load is such that the action of gravity effects the tilting action of the wagon body to discharge the load and at the same time the tail board acting as a counter-weight is raised. This counter-weight in descending assists in causing the body to readjust itself to its normal position. Thus the tilting and dumping action are performed by the direct action of gravity and the wagon body is readjusted by the indirect action of the same force. The tail-board in acting as a counter-weight or potential energy accumulator thereby becomes the means by which the kinetic energy exerted in dumping the load may be used in effecting readjustment of the body.

In the accompanying drawings I have illustrated one form of a convenient embodiment of my invention and in the said drawings:—Figure 1 is a perspective of a wagon made in accordance with my improvement, the body being in its normally adjusted position. Fig. 2, a rear elevation of a wagon. Fig. 3, a view similar to Fig. 1 showing the body of the wagon in a position for dumping, the tail board being elevated.

In carrying out my invention as here embodied, A represents the ordinary side bars of the frame of a dumping wagon mounted upon the usual wheels B and B', and C represents the body of the wagon pivoted to the rear axle D by the straps and sleeves E so that it may freely swing when being dumped and readjusted, as will be readily understood. The body is so located that the greatest portion thereof is back of the rear axle. The tail board F is secured to the outer ends of the levers G the inner ends thereof being pivoted to the brackets H which are attached to the sides of the body of the wagon. To the side bars A are secured the arms I which extend outward and

upward and their outer ends are forked as indicated by J to form a rocking point for the levers G when the body is being dumped and readjusted.

5 J' denotes pins which are placed in the upper ends of the forked portion J of the arm I to prevent the levers G from leaving their place in the forked portion of the arms I, but when the wagon is to be loaded with 10 something which is very heavy which would be very hard to lift over the sides of the body the pins J' may be removed and the tail board lifted and swung forward until it rests upon the top of the wagon body. To 15 the front portion of the frame below the seat are fastened the rods K which extend rearward and have their rear ends forked as indicated by L for attaching them to the arms I thus bracing said arms. To the 20 front portion of the inner frame is pivoted the lever N having the foot piece O in easy reach of the driver, and this lever is connected by the rod P to the latch Q the nose of said latch being adapted to engage the lug 25 or timber R projecting from the front portion of the wagon for the purpose of locking the body in its closed adjustment.

S represents an elliptical spring so secured upon the frame of the wagon that the front 30 portion of the body will come in contact with and compress the spring and hold it so compressed by the latch Q engaging with the lug or timber R.

From the foregoing description the operation 35 of my improvement will be as follows: When the latch Q is released the action of gravity will cause a tilting movement of the wagon body to discharge the load or contents. The expansive action of the spring 40 S when said latch is released assists in causing the initial tilting movement of said body; but the principal purpose and function of said spring is to act as a buffer for the front end of the body when it returns to 45 normal position. Said spring, however, is not essential even for this purpose, nor is it 50 essential to the automatic operation of the wagon body in tilting to dump the load. As the body swings for dumping, the tail board will be swung upward as clearly shown 55 in Fig. 3 by the connection of the lever G with the bracket H and resting on the rocking point of the arms I. As soon as the load has been cleared by the forward movement 60 of the wagon the weight of the tail board will cause said body to swing to its readjusted or closed position compressing the elliptical spring S and locking it by the engagement of the latch Q with the timber R, 65 and this operation will take place with but little attention on the part of the driver, it being only necessary for him to press forward upon the foot piece O of the lever N to cause the wagon to dump, then start the 70 team forward to cause it to readjust and

lock. By the use of my improvement much time and labor and annoyance will be saved, giving the driver much better control of the team.

T represents short chains one end of each 70 of which is secured to the frame, the opposite ends to the body which limit the downward movement of the rear portion of the body to the position shown in Fig. 3 when the lower end of the body is in line with the 75 wheels.

As has already been indicated, the portion 80 of the body in rear of its pivotal connection to its support is somewhat longer than the portion thereof in front of such support.

This extra length of body provides for a greater cubical contents and a consequent 85 preponderance of weight in the rear of such pivotal support when the wagon is loaded.

On the other hand, when a body is empty 90 the preponderance of weight is in front of such pivotal support by reason of the fact that at all times the weight of the tail-board of the body is borne by the arms I in consequence of which such tail-board opposes 95

tilting movement of the said body. Furthermore, by removal of the weight of the 100 tail-board from the rear end of the body the front end thereof forward of its pivotal supports which includes the front end board of the body is of greater weight than the portion thereof in rear of said pivotal supports.

Thus the pivotal connection or support upon which the body swings is so situated 105 with reference to the length of the body, that the center of gravity is shifted from a point in front to the rear of such pivotal connection when a load is placed in the body. It will be understood, of course,

that any other construction or arrangement 110 of the body whereby the cubical contents of the portion thereof in rear of the plane of its point of pivotal connection is greater than the cubical contents of the body in front of such connection will effect the same result.

The function of the levers G is to remove the tail-board F from the end of the wagon body and at the same time to act as a powerful leverage to cause it to assist 115 in returning the body to its normal position as shown in Fig. 1. By reason of the sliding action of the levers G upon their fulcrums the greatest leverage or thrust of the tail-board F is exerted upon the wagon body at the time it is most needed, that is,

120 after the load has been discharged from the wagon body and such body is about to return to its normal position.

In operating a dumping wagon embodying my invention, the operator or driver 125 releases the latch Q and if the body is loaded the center of gravity of the combined weight of the body and its load is located in rear of the pivotal connection or support of the body so that the said body is at once tilted, 130

the load being thereby discharged, the tail-board F which acts as a counter-weight is raised and thereby acquires a sufficient amount of potential energy which, in connection with the portion of the body which is in front of its pivotal connection or support, acts to force the body back into its normal position.

Of course I do not wish to be limited to the exact details of construction here shown as these may be varied within certain limits without departing from the spirit of my invention.

Having thus fully described my invention, what I claim as new and useful, is—

1. In a dumping wagon having a frame, the combination of a pivotally supported wagon body, the center of gravity of said body when empty being forward of its pivot and the center of gravity of the combined body and load carried thereby being in rear of said pivot, a tail-board for said body, curved levers pivoted to said body and rigidly secured to said tail-board, bifurcated arms carried by said frame, and slidably supporting said levers in rocking relation therewith, and a spring carried by said frame tending to uplift the forward end of said body and thereby supplement the ac-

tion of gravity and forming a buffer for said body when returned to its normal position, after being dumped.

2. In a dumping wagon having a frame, the combination of a tilttable body pivoted to rock on said frame, its greater portion extending rearward of its pivotal axis, a relatively movable tail-board for said body, downwardly curved levers pivoted to said body and secured to said tail-board, means supporting the curved portion of said levers in slidable rocking relation, and means tending to uplift the forward end of said body and operative as a buffer when said body is returned to its normal position, and means for locking said body in normal position opposed to said buffer, the curved levers being coöoperative with their supporting means to effect the greatest leverage upon the wagon body when in its dumped position, said leverage gradually diminishing as said body is returned to its normal position.

In testimony whereof, I have hereunto affixed my signature in the presence of two subscribing witnesses.

JOHN F. HUGHES.
